MACHINE FOR PRESS FORMING SHEETLIKE ARTICLES

Samuel H. Miller, Cleveland, Gordon L. Jenkins, Lakewood, and Frederick T. McGuire, Jr., Shaker Heights, Ohio, assignors to Industrial Fabricators Inc., Cleveland, Ohio, a corporation of Ohio

Application November 18, 1942, Serial No. 466,078

2 Claims. (Cl. 144—257)

The invention relates to apparatus for deforming sheet, and more specifically to apparatus for simultaneously producing a plurality of bending operations on flat sheet of wood-like, synthetic nature.

While the invention may be used with little or no modification to produce permanent deformations in sheets from a wide variety of materials of this general type, the description hereinafter given involves the production of a trough shaped, elongated reflector made from a board formed by synthesis of exploded wood fiber. It should be understood that the specific example illustrated and described is descriptive merely, and not limiting.

One object of the invention, therefore, is the provision of a simple yet efficient apparatus for producing, simultaneously, a plurality of deforming operations on sheet material.

A further object is the provision of an apparatus of this nature, wherein improved means are provided for the application of heat and pressure to a plurality of spaced locations on the sheet.

A further object of the invention is the provision of an apparatus such as just described, and wherein improved means are provided for guiding, controlling, and evenly distributing the application of the deforming pressure.

Other objects and advantages will be apparent to those skilled in the art on consideration of the following description, in conjunction with the attached drawings illustrating one specific embodiment of the invention.

Fig. 1 is a perspective view of an apparatus embodying the invention;

Fig. 2 is a perspective view of a trough shaped reflector, after its formation on the apparatus shown in Fig. 1;

Figs. 3, 4 and 5 are transverse vertical sections taken on the line 5—5 of Fig. 1, Figs. 3 and 4 however showing certain parts in positions other than as shown in Figs. 1 and 5; and

Figs. 6 and 7 are detail views, in section of slightly modified portions of the apparatus shown in Figs. 1, 3, 4 and 5.

Before the present invention is described in detail, it is to be understood that the invention here involved is not limited to the details of construction or the specific arrangement of parts herein illustrated or described, as the invention obviously may take other forms. It also is to be understood that the phraseology or terminology herein employed is for the purpose of description and not of limitation, the scope of the

present invention being indicated by the appended claims.

The apparatus here illustrated consists, in essentials, of a lower die or bed having suitable supporting means therefor, heating means for said bed, means for positioning a sheet-like article on said bed, and means for applying to said article, when thus positioned, a deforming force at a plurality of spaced locations on said sheet, and particularly outwardly beyond the bed edges, the pressure being maintained for a period necessary to plastically deform the sheet. Further means are provided for controlling the pressure within proper bounds, and for evenly distributing the pressure. One of the significant features of the invention is the presence of means which permits regulation of the pressure to a value insufficient to exceed the cold elastic limit of the material, but sufficient to produce permanent deformation of the material above a critical temperature. In the specific embodiment here shown such pressure regulation is accomplished by varying both the absolute pressure and its zone of application to the sheet, due consideration being given to the thickness and specific grade of the material.

In view of the aforesaid it is apparent that the deforming pressure might be supplied from various sources, hydraulic, electrical, mechanical, or various arrangements involving two or more of such sources. The relatively simple arrangement shown in the attached drawings utilizes gravity, augmented in part by a leverage arrangement, to furnish the deformation pressure, and when the operation is completed the pressure load is removed by a conventional hydraulic power hoist, using compressed air to produce the power stroke of the piston. When the next work piece is ready to be deformed, the cylinder is valved to exhaust, and the next operation again takes place under gravity.

Proceeding now to a specific description of the embodiment shown in the drawings, reference numerals 10 indicate four upright frame members or corner posts rigidly secured in fixed alignment by horizontal stiffeners comprising two longitudinal frame bars 12 and two cross bars 13 at or near the base. Two longitudinal frame members 14 are securely attached to the uprights near or at their tops.

At an intermediate height, approximating a convenient working level, a bed assembly is carried by two cross bars 15 and 16 which are rigidly attached to uprights 10. The bed assembly may be constructed in any suitable way but

one convenient method is here illustrated which is particularly adapted for the manufacture of a trough like reflector 17 such as is shown in perspective in Fig. 2. The bed assembly consists of two elongated hollow cylindrical members 18 and 19 carried in parallel arrangement by a spacing and supporting member 20 which is here conveniently represented by an I beam, the cylindrical members being welded or otherwise firmly attached to the beam 20. Beam 20 is carried by, and affixed to, cross members 15. For the manufacture of the particular shape shown in Fig. 2, the upper outer quadrants of cylinders 18 and 19 represent the actual forming faces of the bed assembly, as will appear as the description proceeds.

Heating means is provided for the cylinders 18 and 19, such means in the present instance consisting of elongated, perforated gas burners 22 and 23 supported respectively within cylinders 18 and 19 by spiders 24 and 25. The burners are fed in the usual way through flexible couplings 26 and 27, and are valved in conventional manner, as shown at the left of Fig. 1. Suitable flues 28 and 29 are also provided, as shown towards the right of Fig. 1.

The pressure applying means hereinafter termed the head, will now be described. The drawings show a longitudinally disposed structural member or I beam 32 positioned above and in the present embodiment generally parallel to the beam 20 already described. Attached to the base flange 33 of the I beam by suitable hinges 34 are two angle members 30 and 31 coextensive in length with beam 32, and so disposed that their vertical flange portions 36 and 37 lie somewhat outside cylinders 18 and 19. Attached respectively to angle members 30 and 31 by welding or otherwise are two projecting wing brackets 38 and 39 which may be conveniently formed from channel sections. These wing members respectively carry loading weights 40 and 41, which weights may be arranged to be replaceable, either by removal and substitution, or by removal of the wing members 38 and 39. The wing members carry respective eye bolts 45 and 46 which are retained by means of nuts 47 as will be apparent.

Beam 32 is maintained in parallel alignment with beam 20, while capable of approaching and receding motion relative thereto, by guiding and aligning means now to be described. Since each end of the machine is provided with such identical guiding and aligning means, only one such means will for simplicity be described.

Beam 20 carried near its end, and projecting normally to its upper flange, a rod 50. Beam 32 is perforated by two vertically aligned openings in which is fixedly seated, by welding or otherwise, an elongated bushing 51. Bushing 51 slides telescopingly on rod 50 with sufficient clearance to allow beam 32 to be freely raised and lowered with respect to beam 20. Provision of such aligning means at both ends of the machine maintains the beams in parallel alignment. Such alignment is subject to further adjustment by means of compression springs 53 which are maintained between flanges 54 on the bushings and adjustable collars 55 on rods 50.

As will subsequently appear, the assembly just described, comprising the beam 32, the angles 31 and 30, and the wings 38 and 39, supplies the deforming force which simultaneously produces a plurality of bends in a synthetic wood sheet. This assembly is elevated in the following man-

ner. In connection with this description, see Figs. 1, 3 and 5.

A bracket, generally indicated by reference numeral 60, is transversely disposed upon, and permanently attached to, top frame members 14, at about the mid point thereof. Bracket 60 carries two spaced, upright, bifurcated members 61 and 62 which respectively support levers 63 and 64, said levers being mounted in swinging relationship on pivots 65 and 66. Levers 63 and 64 have their outer ends connected to the upper ends of two hoisting chains 67 and 68, which chains are in turn respectively connected, at their lower ends, to eye bolts 45 heretofore described.

Bracket 60 also carries a conventional hydraulic power apparatus comprising a cylinder block 70 in which a piston 71 is reciprocably slidable, the piston being actuated in one direction by compressed air supplied to a chamber 80 through line 72 under the control of a three way valve 73 arranged either for the admission of air, or the exhaust thereof. Piston 71 is affixed to a rod 74 (Fig. 5) which is movable vertically through an opening in bracket 60. A conventional extensible dust cap 75 prevents the entry of dust to the cylinder interior through the rod packing. The upper end of the rod is suitably linked to the inner adjoining ends of levers 63 and 64, by a chain connection 76 or otherwise.

The raising and lowering of the head proceeds as follows: Assuming the head to be in its lowest position, shown in Fig. 5, compressed air is admitted to the upper chamber 80 of the cylinder by suitable operation of valve 73. This causes piston 71 and rod 74 to move downwardly, thereby swinging lever 64 counterclockwise and lever 63 clockwise, elevating chains 67 and 68 and raising wings 38 and 39 and the affixed angles 30 and 31 which assembly in a preliminary phase of the operation, merely pivots on hinges 34 without producing upward motion of beam 32. Angles 30 and 31, however, are respectively equipped with upwardly directed, projecting studs 83 and 84 which, by said pivotal motion around hinges 34, are brought into contact with abutment brackets or pads 85 and 86. Further hoisting motion of chains 67 and 68 lifts beam 32, causing bushings 51 to slide upwardly on rods 50 against the snubbing action of springs 53, as best shown in Fig. 3, which indicates approximately top position of the head, corresponding to extreme inward travel of the piston 71 in the cylinder.

This position may be maintained as long as desired. The head assembly is lowered by venting the chamber 80 of the cylinder to exhaust by means of valve 73. The compressed springs 53 assist in starting the head downwardly and the weight of the head assembly, exerted at the outer ends of levers 63 and 64, and transmitted to piston rod 74, returns the piston 71 to top position as indicated in Fig. 5, the head descending meanwhile. To facilitate this operation the lower chamber 90 of the cylinder is vented to atmosphere through stub pipe 91, which may carry a conventional air cleaner and filter 92.

The manner of formation of a sheet article of wood like material to a contour such as shown in Fig. 2 will now be described. This specific article, a trough shaped reflector having opposed, convexly curved portions 94 and 95, is used as a substitute for a similarly shaped article previously formed from a metal which is now of

strategic character, and hence such material substitution is highly desirable.

A sheet of material of suitable area and thickness is first allowed to soak in water for a number of hours, the moisture penetrating the fibers and conditioning the sheet for the bending operations. With the head in fully elevated position, as shown in Fig. 3, and with the cylinders pre-heated to desired temperature as previously described, the sheet 17a is inserted from right to left (Fig. 3) until its leading edge abuts a stop 96 which is carried by frame post 10. Two such stops may be provided, one at each end of the frame. For convenience the stop 96 may be adjustably mounted by means of slots 97 and bolts 98 on fixed brackets 99, the brackets in such instance being fixed on the frame posts 10. When thus placed in position the sheet is in line contact with cylinders 18 and 19 of the bed assembly, its middle portion being out of contact with said cylinders, as shown in Fig. 3. Proper manipulation of valve 73, as heretofore described permits the head to descend until the lower flange of the beam 32 makes contact with the sheet 17a. In the embodiment here shown, a pressure pad 100 is provided along the lower contacting face of beam 32, such pad being conveniently formed from several laminations of the same material as sheet 17a, and being retained in fixed relationship to the beam by machine screws or bolts 101, the screw head seats being countersunk in the bottom surface. In such instance the pad establishes the preliminary contact between the head and sheet 17a.

Such contact having been established, the dead weight of the head assembly confines and maintains sheet 17a in fixed position on the cylindrical elements 18 and 19 of the bed. The hingably mounted side assemblies comprising angles 30 and 31 and wings 38 and 39 continue to move downwardly until contact is established between the sheet and the elongated, narrow abutment formed by the lowermost edge portion 105 of angle member 31. Since the operation of both hinged side elements of the head is identical, the action of one only is described, reference now being had to Figs. 3 and 4. As the weight of the angle member 31 and its wing 39 is applied to sheet 17a through the medium of angle edge abutment 105 which is outwardly positioned beyond cylinder 19, the sheet first yields resiliently without permanent set, at the same time being bowed upwardly at its central portion 106 so as to slightly raise the beam 32 against the resistance of springs 53. At first the sheet contacts with the heated cylinders only along two parallel lines. In a short time the heat softens it along these lines so that it begins to bend with a permanent set at those lines. As the hinged assembly descends further the effect is to extend the area of contact between heated cylinder 19 and sheet 17a, the effect of the heat and moisture on the sheet producing an increasing plasticizing or softening action locally throughout the area of actual contact, so as to cause the sheet progressively to acquire a local permanent set of the specific shape of the contacting portion of the bed. Downward gradual motion of the wing elements continues, under gravity, until a stop member 110 makes contact with a bracket or other abutment 111 carried at the cylinder ends (Figs. 1 and 5). The length of the stop 110 and the position of bracket 111 are so arranged that the downward motion of the head is terminated when the desired contour, as shown in Fig. 2 is imparted to

the sheet. Since the middle portion of the sheet is never in contact with the cylindrical formers it never becomes heated sufficiently to become as plastic as other portions of the sheet. Therefore, as the bending operation proceeds, this middle portion, which at first arched upwardly as in Fig. 4, finally relaxes to its original flat form, as in Figs. 3 and 5. To allow for some slight residual resiliency in the opposed convex portions of the reflector the stop 110 may be disposed to allow the side portions 11c of the reflector to be carried somewhat past the required angular deflection since, when the pressure is removed, the side portions tend to spring back slightly.

It is obvious that articles of various contours may be produced by proper variation in the extent and contour of the head and bed portions. Other such changes can be effected by a change in the dimensions and lateral spacing of the vertical portions 36 and 37 of the hinged angle members which, of course, need not be identical in either size or contour with each other.

The weight of the wing members 38 and 39 may be varied to produce desired changes in pressure resulting from the varied requirements of sheets of respectively varying thicknesses. The weights 40 and 41 may be made to be adjustable in distance from the fulcrums 34, as shown, for instance, in Fig. 6 where a flat plate 38a is provided with a slot 112 which serves as a track for a movable counterweight 113. The counterweight is retained by a suitable threaded stud 114 and washer 115. The eye bolt 116, corresponding in function to bolts 45 and 46 previously described, is adjustable in length, as shown.

The utilization of a pressure head assembly of the nature described has a number of advantageous features. For instance the cylinders 18 and 19 may be replaced by others of smaller or larger outside diameter, depending on the radius desired in the fabricated article. Other curved or variously contoured edge portions may be substituted for the cylinders. The use of a pressure edge or elongated narrow abutment, such as 105, for the application of the bending force along a line eliminates a substantial proportion of the large frictional losses encountered when a full-contact die face is used to form material. As seen for instance in Fig. 3 the edge 105 is rounded to provide for low friction slippage along the upper surface of the sheet after first contact, as already described. The angle of impingement of edge 105 against the sheet may be altered, and its distance from the fulcrum 34 otherwise varied, as desired.

Fig. 7 shows a slightly modified form of the invention wherein the edge 105 of angle 31 is provided with a contacting pad 117 of softer material than metal, and preferably of the same material as that being formed. This reduces any tendency of the contacting edge to scuff or mar the material.

The invention has been described with special reference to synthetic wood sheet of disintegrated and pressed wood fibers since this material has in the past given rise to serious problems. As a matter of fact no previous successful method or apparatus is known for simultaneously producing a double bend such as here shown. Other types and configurations involving bending operations of varied character may be produced by modifications in the apparatus here shown and described, such modification being a simple matter for a mechanic after consideration of the present invention.

What we claim is:

1. Apparatus for bending work sheets of wood-like material to channel form, comprising a frame, an elongated bed supported thereby, and having convexly curved, spaced, parallel side forming portions, heating means therefor, said bed being adapted to receive and support a work sheet with its side edges extending outwardly beyond said curved side forming portions, a forming head mounted in the frame for vertical movement above said bed and including an elongated platen having a work confining surface of approximately the same width as the space between the side portions of the bed, and a swinging bender hinged to each side edge of the platen and provided with an elongated narrow abutment lying outwardly beyond the adjacent forming portion of the bed, the platen and the benders being relatively of such weight and the arrangement being such that when the forming head is lowered upon a moistened work sheet lying upon the bed the weight of the two benders at first arches the middle portion of the sheet and holds the sheet applied to the heated bed along two lines and then progressively bends the outer edge portions of the sheet downwardly to conform them to the curved forming portions of the bed while the middle of the sheet relaxes to flat form.

2. Apparatus for bending work sheets of wood-

like material to channel form, comprising a frame, two cylindrical formers supported thereby in spaced parallel relation at the same level, heating means therefor, said formers being adapted to contact with and support and heat a work sheet at first along two lines only, leaving the intervening middle portion of the sheet free of contact with and support by them and with the side sheet edges extending outwardly beyond said former, and a forming head vertically movable in the frame above said formers, said head including a platen portion wide enough to bridge the space between said formers and including two narrow bending abutments movably connected thereto, said abutments extending parallel to the axes of the formers and lying outwardly beyond the same, whereby upon downward movement of the head the abutments engage the outer portions of a work sheet along two lines and progressively bend the sheet around and apply it to the formers as the sheet becomes plastic by contact therewith, and whereby also the middle portion of the sheet which is out of contact with the formers at first arches upwardly and then relaxes to flat form.
